UNITED STATES PATENT OFFICE

127,499

DESIGN FOR A COMBINED WASHING MACHINE AND WRINGER

Henry J. Goldblatt, Chicago, Ill.

Application June 29, 1940, Serial No. 93,331

Term of patent 7 years

To all whom it may concern:

Be it known that I, Henry J. Goldblatt, a citizen of the United States, residing at Chicago, in the county of Cook and State of Illinois, have invented a new, original, and ornamental Design for a Combined Washing Machine and Wringer, of which the following is a specification, reference being had to the accompanying drawings, forming a part thereof.

Fig. 1 is a front perspective view of a combined washing machine and wringer showing my new design; and

Fig. 2 is a rear perspective view thereof.

I claim:

The ornamental design for a combined washing machine and wringer, as shown.

HENRY J. GOLDBLATT.
